(57) **CLAIM**

The ornamental design for the modular plug, as shown and described.

DESCRIPTION

FIGS. 1-2 are first and second exploded perspective views of the modular plug in accordance with the principles of the present invention;

FIGS. 3-4 are first and second exploded side plan views of the modular plug;

FIGS. 5-6 are first and second axial views of the modular plug;

FIGS. 7-8 are first and second perspective views of the modular plug in the assembled condition thereof; and,

FIGS. 9-10 are first and second side plan views of the modular plug in the assembled condition thereof.

The portions of the figures shown in broken lines are for illustrative purposes only and form no part of the claimed design.
